Specification for Design.

Patented Dec. 19, 1911.

Application filed June 17, 1911. Serial No. 633,908. Term of patent 7 years.

To all whom it may concern:

Be it known that I, EDWIN L. WHITE, a citizen of the United States, residing at the borough of Brooklyn, in the county of Kings and State of New York, have invented a new, original, and ornamental Design for Extension-Rings and Body-Shells for Chandeliers and Lighting-Fixtures, of which the following is a specification, reference being had to the accompanying drawing, forming part thereof.

Figure 1 is a plan view of an extension ring or body shell showing my new design, and Fig. 2 is a cross section of the same.

I claim:

The ornamental design for an extension ring and body shell for chandeliers and lighting fixtures, as shown.

EDWIN L. WHITE.
